(57) **CLAIM**

The ornamental design for a cover for microscope eyepiece, as shown and described.

DESCRIPTION

FIG. 1 is a front perspective view of a cover for microscope eyepiece showing my new design.

FIG. 2 is a top view of the cover for a microscope eyepiece of FIG. 1.

FIG. 3 is bottom view of the cover for a microscope eyepiece of FIG. 1.

FIG. 4 is a right-side view of the cover for a microscope eyepiece of FIG. 1.

FIG. 5 is a left-side view of the cover for a microscope eyepiece of FIG. 1.

FIG. 6 is a back view of the cover for a microscope eyepiece of FIG. 1; and,

FIG. 7 is a front view of the cover for a microscope eyepiece of FIG. 1.

The broken lines in the drawings depict environmental subject matter only and form no part of the claimed design.
